UNITED STATES PATENT OFFICE.

DAVID C. PRINCE, OF SCHENECTADY, NEW YORK, ASSIGNOR TO GENERAL ELECTRIC COMPANY, A CORPORATION OF NEW YORK.

ELECTRON-DISCHARGE APPARATUS.

Application filed April 8, 1922. Serial No. 550,752.

To all whom it may concern:

Be it known that I, DAVID C. PRINCE, a citizen of the United States, residing at Schenectady, in the county of Schenectady, State of New York, have invented certain new and useful Improvements in Electron-Discharge Apparatus, of which the following is a specification.

My present invention relates to electron discharge devices and more particularly to circuit connections which may be employed with such devices.

The object of my invention is to improve the efficiency of operation of electron discharge devices.

One of the principal losses incident to the operation of an electron discharge device is that due to the space charge drop between filament and plate. It has been known that this drop in potential between filament and plate might be greatly reduced by the use of a positively charged grid interposed between filament and plate. This method of operation has not been employed to any extent, however, because of the fact that it is necessary in order to produce any substantial reduction in the space charge drop to impress quite a high positive potential on the grid, and as a result the grid itself receives so many electrons that the grid losses will more than compensate for the gain obtained through reduction in the space charge drop.

The grid losses introduced in this manner, however, are partly due to the fact that as the grid potential is increased the velocity of the electrons which reach the plate will be increased and secondary electrons will be emitted. These secondary electrons will be attracted to the grid and the effect will be a withdrawal of energy from the plate circuit and absorption of energy by the grid circuit.

In carrying my invention into effect I overcome the above disadvantage by providing means for preventing the escape of secondary electrons from the plate. This means may conveniently take the form of a grid interposed between the control grid and the plate. If, when current is flowing to the plate this extra grid is made slightly negative with respect to the plate no secondary electrons can escape from the plate and the control grid may be made positive enough to greatly reduce the space charge losses

without introducing compensating grid losses.

The novel features which I believe to be characteristic of my invention are set forth with particularity in the appended claims. My invention itself, however, both as to its organization and method of operation will best be understood by reference to the following description taken in connection with the accompanying drawing in which Figs. 1 and 2 show diagrammatically two different circuit organizations whereby my invention may be carried into effect.

I have shown in Fig. 1 an electron discharge device 1 having the usual filamentary cathode 2, control grid 3 and plate or anode 4. An extra grid 5 is interposed between the control grid 3 and the anode 4. An oscillating circuit comprising inductance 6 and capacity 7 is connected between the control grid and anode, an intermediate point 8 of the inductance 6 being connected to the cathode. A source of energy 9 connected between cathode and anode furnishes the energy for feeding the oscillating circuit. A choke 18 prevents the high frequency energy from being short circuited through the source 9 and a condenser 11 prevents the direct current from being short circuited through inductance 6. The extra grid 5 is connected to a point 12 in inductance 6 intermediate the point 8 and the end to which the control grid 3 is connected. The grid 5 will oscillate in potential with the grid 3 and the amount of its swing can be so adjusted that it will become just enough positive to permit the maximum current to flow to the plate, and not positive enough to permit it or grid 3 to receive secondary electrons emitted from the plate. High frequency oscillations produced by this arrangement may be supplied to a coil 13 which is coupled to the inductance 6 and supplied from coil 13 to any form of utilization circuit desired.

In the arrangement shown in Fig. 2 the desired results are brought about in a somewhat different way. In this case an inductance 14 is included in circuit between the source of current 9 and the plate 4. The extra grid 5 is connected to a point in this inductance beyond the plate connection. With this arrangement the extra grid and

- plate will oscillate in potential together, but the potential of the extra grid will always be enough below that of the plate while electrons are passing to the plate to prevent secondary emission. In this case also electrons collected by the extra grid 5 constitute useful output the same as though they were received by the plate itself. In this case the coil 15 in the grid circuit may be coupled to the coil 14 in the plate circuit to furnish the necessary feed-back coupling for producing oscillations although the condenser 7 will ordinarily furnish the only coupling necessary.
- 15 The operation of devices such as I have described may also be improved by the use of a black body as anode, that is, an electrode having a surface of such a nature that it does not readily emit secondary electrons.
- 20 This tendency to emit secondary electrons may be reduced by providing a rough surface on the electrode and by the selection of the material used for the electrode, copper or nickel, for example, showing much less 25 tendency to emit secondary electrons than tungsten or molybdenum.

While I have shown and described my invention in connection with systems for the automatic generation of electrical oscillations, my invention is by no means limited to this particular application as it may be employed to advantage in other cases, as for example, in the case where oscillations are produced through the relay action of 35 such a device, or in cases where it may be desirable to employ a device having a control grid for the rectification of alternating currents.

What I claim as new and desire to secure 40 by Letters Patent of the United States, is:—

1. An electron discharge apparatus comprising a device having an electron emitting cathode and a cooperating anode, a grid interposed between cathode and anode, means 45 for impressing a positive potential upon said anode to permit the flow of electrons from cathode to anode, means for impressing a higher positive potential upon said grid during the time when it is desired to have current flow to the anode, a second grid interposed between the first grid and the anode, and means for maintaining the second grid at a lower potential than the anode during the time when current flows to the anode.
- 55 2. An electron discharge apparatus comprising a device having an electron emitting cathode, an anode and a control grid, a source of potential and an oscillating circuit associated with said anode and means for 60 producing oscillations therein, a second grid interposed between the control grid and the anode, and means for impressing upon the

second grid during periods when current flows to the anode, a potential less positive than the potential of the anode.

65 3. An electron discharge apparatus comprising a device having an electron emitting cathode, an anode and a control grid, a source of potential connected to said anode, an oscillating circuit associated with said anode and grid in such a way that oscillations will be produced therein by the action of said control grid, a second grid interposed between the control grid and the anode, and means for impressing upon the 70 second grid, during periods when current flows to the anode, a potential less positive than that of the anode.

75 4. An electron discharge apparatus comprising a device having an electron emitting cathode, an anode and a control grid, a source of potential connected to said anode, an oscillating circuit associated with said anode and grid in such a way that oscillations will be produced therein by the action of said control grid, a second grid interposed between the control grid and the anode and a connection between said oscillating circuit and said second grid for impressing upon the second grid, during periods when current flows to the anode, a potential less positive than that of the anode.

80 5. The method of operating an electron discharge device having an electron emitting cathode, an anode and two grids interposed between cathode and anode which consists in impressing a positive potential on the anode to produce a flow of current between cathode and anode, controlling the flow of current to produce oscillations by impressing a variable potential upon the grid nearest the cathode and preventing the escape of 85 secondary electrons from the anode by impressing upon the grid nearest the anode a positive potential lower than that of the anode.

90 100 6. The method of operating an electron discharge device having an electron emitting cathode, an anode and two grids interposed between cathode and anode, which consists in impressing a positive potential on the anode to produce a flow of current between cathode and anode, varying the potential of the grid nearest the cathode to produce oscillations and causing the potential of the grid nearest the anode to oscillate with that of one of the other electrodes but in such a way that when current flows to the anode the potential of the second grid will always be negative with respect to the anode.

105 110 115 120 In witness whereof, I have hereunto set by hand this 7th day of April, 1922.

DAVID C. PRINCE,
